UNITED STATES PATENT OFFICE

2,222,434

COIN CONTROLLED LOCK MECHANISM

George Hofmann, Boston, Mass., assignor, by
mesne assignments, to American Locker Com-
pany Inc., Boston, Mass., a corporation of Dela-
ware

Application April 5, 1937, Serial No. 134,959

2 Claims. (Cl. 70—436)

This invention relates to coin controlled lock mechanisms of the type disclosed in Patents Nos. 1,640,605 and 1,933,263, and the primary object of the invention is the production of a lock mechanism of this nature having various novel improvements which render it superior to like mechanisms heretofore known.

These lock mechanisms are used on checking and vending cabinets and are operative for checking and vending purposes upon the insertion of a coin. Each such lock mechanism includes a body member within and on which are mounted not only the coin controlled lock but also a second lock arranged to secure such mechanism in and to the cabinet. Occasionally and for various reasons it becomes necessary to change either the coin controlled lock or the said second lock, and heretofore either requirement has necessitated the changing of the entire lock mechanism due to the substantial integral mounting of the second lock thereon. One object of my invention herein is the production of an improved mechanism wherein one or the other of such locks can be changed without requiring the changing of the other lock.

These coin controlled locks are adapted normally to remain either in the locked or unlocked position, but in the construction heretofore employed it has occasionally happened that the lock would inadvertently move from that position and thereby permit unauthorized operation thereof without the insertion of a coin. A further object of my invention is a novel improvement wherein such inadvertent movement is rendered impossible.

It is well known that recording or counting mechanism is combined with the coin controlled lock to record each actuation thereof whereby registering the number of coins deposited. Heretofore no resetting mechanism has been incorporated in the recorder since such mechanism would permit the collector to fraudulently reset the recorder to a fictitious position other than that showing the number of coins actually deposited. A further novel feature of the invention relates to a mechanism for resetting the recorder whenever such action becomes necessary and to further mechanism for preventing unauthorized operation of such mechanism.

These and other features of the invention will be best understood and appreciated from the following description of a preferred embodiment thereof selected for purposes of illustration and shown in the accompanying drawings in which,

Fig. 1 is a front elevation of a cabinet employing my improved lock mechanism,

Fig. 2 is a sectional view taken on line 2—2 of Fig. 1 and showing the lock mechanism in side elevation,

Fig. 3 is a sectional view taken on line 3—3 of Fig. 2 and showing the lock mechanism in front elevation,

Fig. 4 is a fragmentary sectional view taken on line 4—4 of Fig. 2,

Fig. 5 is a sectional view taken on line 5—5 of Fig. 3 and showing the lock mechanism in plan view,

Fig. 6 is a sectional view taken on line 6—6 of Fig. 2 and showing the lock mechanism in rear elevation,

Fig. 7 is a fragmentary sectional view taken on line 7—7 of Fig. 2,

Fig. 8 is a fragmentary view taken on line 8—8 of Fig. 3,

Fig. 9 is a side elevation of the recorder showing the rear portion thereof in section,

Fig. 10 is a perspective view of the rearmost and units counter,

Fig. 11 is a perspective view of the inner face of a closure member for the recorder.

Referring more specifically to the drawings, 10 indicates a bank of coin controlled checking cabinets, and 12 the closure door of one of the cabinets. The lock mechanism 14 is secured to 30 a marginal portion of the cabinet in position to cooperate with and lock the door. This lock mechanism comprises a body member 15 having a front plate 16 secured thereto by bolts 18. The front plate is disposed over and fills an opening 35 through the cabinet wall, the lower end of the plate being provided with a lip 19 engaging behind the cabinet wall and the upper end being equipped with a lock 20 having a lock bolt 21 for engaging behind the cabinet wall (Fig. 2).

The cylinder of the lock 20 is adapted to rest in the lower half 22 of a cradle formed on the top end of the member 15, the upper half 24 of the cradle being an independent piece and having a sliding dove-tailed fit into the member 15 at 45 25. The cylinder shell is prevented from rotating by a laterally projecting and tumbler-containing arm 26, and a spring 28 keeps the lock in its foremost position. The portion 24 of the cradle is secured to the member 15 by the upper 50 bolts 18 engaging ears 17.

The cabinets are distributed to various agencies, and each agency is provided with a key fitting all the locks 20 of its cabinets. It occasionally happens that this key becomes lost and falls 55

into the hands of one who uses it in an unauthorized manner. Under such circumstances it is necessary that the locks 20 be changed. In this case, with the lock mechanism heretofore known, as those illustrated in the aforementioned patents, it has been necessary to change the entire lock mechanism, whereas my invention herein permits the changing of only the lock 20. When such a change is necessary the agent unlocks the lock 20 and removes the entire lock mechanism. He then removes the lock 20 and substitutes another in its stead merely by removing the upper bolts 18 and the upper portion 24 of the cradle. It will be quite apparent that such improvements not only eliminate the necessity of discarding the entire coin controlled lock mechanism, but furthermore, that it makes such change an easy and quick matter, entailing no delays in the use of the cabinets.

20 The cylinder 30 of the coin controlled lock is rotatably mounted in a bore 31 in the body member 15 and is provided with a plurality of tumblers 32 slidably vertically into upper and lower recesses 34 and 35 opening into the bore, the tumblers normally being in the down and locking position when the lock (used for checking) is in the unlocked position of Figs. 3 and 6. When a coin is inserted, the lock may be rotated to locking position by a key 36 and the key may then be removed and carried away as a check, the key being used at some later period to reopen the cabinet and regain the checked parcel. Occasionally it happens that the tumblers will not fall readily into the recess 35 and the key may, under such circumstances, be rotated and removed without having inserted a coin. For the purpose of preventing such unauthorized use of the cabinet, I mount a spring 38 on a post 39 and extend one end 40 of the spring into a recess 42, the other end of the spring bearing against the member 15. The end 40 of the spring is arranged to bear against one of the tumblers and cause it to engage within the recess 35 as illustrated in Fig. 7. In order to facilitate assembling of the tumblers and lock, a shoulder 44 is provided on which the end 40 of the spring may rest during the assembling operation.

Combined with the coin controlled lock on the body member 15 is a recorder 45 having a window 46 through which can be viewed registering members on the rotary counters 48 therein. A connection 50 from the lock serves to rotate the recording mechanism forwardly one digit at each actuating cycle of the lock, thus recording the number of coins deposited. It is quite apparent that fraud might be practiced by unauthorized resetting of the recorder, and for this reason no resetting means has heretofore been provided thereon. It will furthermore be apparent, however, that a resetting means would be a great convenience, as, for example, when a lock or its recorder is removed and transferred to another cabinet and it is desired to start the same at zero. A further feature of my invention therefore includes the provision of a resetting means and further means cooperating therewith for preventing unauthorized operation thereof.

70 The rear end of the recorder housing 45 is closed by a screw threaded disk 52 having a short shaft 53 extending axially therethrough. The shaft carries a rotating head 54 on its

outer end and a disk 56 on its inner end. Projecting inwardly from the disk are two oppositely disposed pins 57 engaging within holes 58 in the adjacent and units counter 48. It will be apparent that the recorder can be rapidly reset by applying a rotating member to the head 54.

As a means of preventing unauthorized use of this resetting mechanism I provide a U-shaped housing 60 having two fingers 62 at one end for engaging in corresponding holes 63 in the body member 15 and having pierced ears 64 for receiving a locking pin 66 therethrough and through a registering hole in the body member 15. A wire 68 is passed through the small end of the pin and the ends are sealed by a metal seal 70. As illustrated in Fig. 8 one side wall of the housing 60 extends over and covers the resetting head 54 whereby preventing the application of a turning instrument thereto, and any tampering with the seal or the housing to gain access to the head for resetting purposes will be clearly detected.

It will now be apparent that I have improved the aforementioned coin controlled lock mechanisms and rendered them more applicable and more convenient to the purposes for which they are used, and my invention furthermore provides for the continued use of portions of the lock mechanism which it has heretofore been necessary to remove and discard.

Having thus described my invention, what I claim as new and desire to secure by Letters Patent of the United States is:

1. In a coin controlled device of the class described, a body member adapted to be mounted on and within a parcel checking cabinet, a lock carried on the body member and operable through a locking-unlocking cycle, a mechanical recorder including a plurality of rotary counters within a housing conforming to and closely confining the counters, a window in the housing through which registering numbers on the counters are visible, a closure for one end of the housing, resetting means extending through the closure axially of the counters and having connection with the adjacent counter, means for actuating the recorder to add one indication thereto at each cycle movement of the lock, an element removably mounted on the body member in position preventing operating access to the resetting means, and means preventing unauthorized removal of the element from such position.

2. In a coin controlled device of the class described, a body member adapted to be mounted on and within a parcel checking cabinet, a lock carried by the body member and operable through a locking-unlocking cycle, an accumulating recorder including a plurality of number disks within a casing conforming thereto and carried on the body member for indicating the number of lock actuations, means for actuating the recorder to add one indication thereto at each cycle movement of the lock, other means including a rotary stud projecting outwardly through a wall of the casing for resetting the disks of the recorder, a U-shaped housing removably mounted on and straddling the body member in position preventing operating access to the stud, and means preventing unauthorized removal of the housing from such position.
